UNITED STATES PATENT OFFICE.

JOHN W. BLYTH, OF GREAT FALLS, MONTANA.

DESIGN FOR A CANE, UMBRELLA, WHIP, OR SWAGGER-STICK HANDLE.

53,193.

Specification for Design.

Patented Apr. 15, 1919.

Application filed August 27, 1918. Serial No. 251,712. Term of patent 14 years.

To all whom it may concern:

Be it known that I, JOHN W. BLYTH, a citizen of the United States, residing at Great Falls, in the county of Cascade and State of Montana, have invented a new, original, and ornamental Design for a Cane, Umbrella, Whip, or Swagger-Stick Handle, of which the following is a specification, reference being had to the accompanying drawing, forming part thereof.

The figure is a perspective view of an umbrella handle showing my new design.

I claim:—

The ornamental design for a cane, umbrella, whip, or swagger-stick handle, as shown.

JOHN W. BLYTH.

Witnesses:

RICHARD BENNETT,
A. SOSNICK.
